UNITED STATES PATENT OFFICE.

NORMAN S. RICHMOND, OF CHICAGO, ILLINOIS, ASSIGNOR TO METAL SPECIALTIES MANUFACTURING COMPANY, OF CHICAGO, ILLINOIS, A CORPORATION OF ILLINOIS.

ELECTRIC LANTERN.

1,174,521.

Specification of Letters Patent.

Patented Mar. 7, 1916.

Application filed March 30, 1914. Serial No. 828,113.

To all whom it may concern:

Be it known that I, NORMAN S. RICHMOND, a citizen of the United States, residing at Chicago, in the county of Cook and State of Illinois, have invented a certain new and useful Improvement in Electric Lanterns, of which the following is a specification.

This invention relates to electric lanterns and has for its object to provide a new and improved lantern of this description.

One of the objects of my present invention is to provide a simple, efficient and effective means of utilizing the ordinary single dry battery to produce a portable electric lantern. The ordinary dry battery is the result of both experience, experimentation and use, and a dry battery, such for example as is known as No. 6, is of universal use and can be purchased for a small price practically any place where general supplies are sold.

This invention is illustrated in the accompanying drawings, wherein;

25 Figure 1 is a front view of a lantern embodying the invention; Fig. 2 is a side view of the device shown in Fig. 1, with portions broken away; Fig. 3 is an inside view of the cover; Fig. 4 is a vertical sectional view 30 through the upper portion of the lantern, taken on line 4-4 of Fig. 1; Fig. 5 shows a modified construction.

Like numerals refer to like parts throughout the several figures.

35 In carrying out my invention, I take a single cell of the common standard dry battery shown as 1 in the drawing and place it in a casing or box 2, having a removable cover 3. The casing or box may be of any 40 suitable material, but is preferably of metal. As illustrated in Fig. 4, the binding post or terminal 4 of the battery 1 is connected to the cover 3 by the conductor 5. This connection may be made in any suitable manner. As herein shown the conductor 5 has a contact 6 which surrounds or engages an insulating bushing 7 and is pressed against the cover by the insulating piece 8, the pressure being provided by the nut 9. Connected 45 with the cover of the casing is an electric lamp socket 10 into which an electric lamp 11 is inserted, the socket 10 engaging the part 12, which forms one terminal of the

lamp. It will be seen that by this construction the binding post or terminal 4 of the 55 battery is electrically connected with the lamp socket 10, the other binding post or terminal 13 of the battery is connected to the other terminal of the lamp in any desired manner. As herein shown there is connected to the terminal 13 a conductor 14, which is connected to a bolt or conductor 16 passing through the cover 3, but insulated therefrom by the insulating bushing 7. Connected with the conductor 16 is a movable switch 65 17 having a handle 18. This switch is adapted to engage(a bolt or switch)contact 19, to which is connected a spring contact 20 engaging the other terminal 21 of the lamp 11. The contact 19 is insulated from the cover 70 3 by the insulating pieces 22. Connected to the cover is a reflector 23 for the lamp 11, said reflector is preferably provided with a removable glass front 24, the lamp being thereby completely inclosed. When the 75 lamp and socket are connected to the cover 3, the body portion of the casing 2 is cut away at 25, so as to permit the end of the lamp socket to project therethrough into the interior of the casing. A suitable handle 26 80 is connected with the casing 3 so that the lantern may be easily carried from place to place.

From the foregoing description, it will be understood that the conductors 5 and 14 85 are carried by and removable with the cover, and that the switch device affords means for making and breaking the circuit between said conductors and the lamp, whose shank extends through the base-portion of the reflector 90 and through the flange of the cover on which the reflector is mounted.

In Fig. 5 I have shown a modified construction in which the switch 17 is pivoted to the contact 19 instead of the conductor 95 16 and is moved to engage the conductor 16 when it is desired to complete the circuit. With this construction the battery will not be short-circuited if the switch 17 should accidentally come into contact with the cover 100 3. In Fig. 5, I have also shown a casing provided with a different form of handle 27.

I have described in detail a particular construction embodying my invention, but it is of course evident that the parts may be 105 varied in many particulars and some of the

parts omitted and others used with parts not herein shown, without departing from the spirit of my invention.

The use and operation of my invention are as follows: In the use of the device a single cell of an ordinary dry battery is secured and the conductor 5 attached to the cover 3 is connected with one terminal of the battery and the conductor 14 connected 10 with the other terminal of the battery. The battery is then placed in the casing 2 and the cover placed thereon. The conductors 5 and 14 are of sufficient length to permit the easy handling of the device. The lantern is 15 now in condition for use. When it is desired to light the lantern, it is only necessary to move the switch 17 so as to connect the two terminals of the lamp with the two terminals of the battery. When it is desired to 20 put out the light, the switch is moved to its off position.

It will be seen that by means of this device, a cheap and efficient electric lantern is provided, which uses a single cell of the 25 ordinary dry battery. This lamp may have a universal use, is not affected by the wind, does not emit disagreeable odors or smoke, eliminates the danger of fire and explosions and can be easily, quickly and cheaply re- 30 newed by removing the old battery and placing a new one in the casing. The lamp 11 is properly proportioned for the voltage and current of a single cell of an ordinary dry battery and the lantern can be used for 35 many days and sometimes weeks, depending upon the extent of the use, without a renewal of the battery.

I claim:

1. An electric lantern comprising a dry 40 battery, a casing therefor, a cover for said casing comprising conducting material, an electric lamp connected with and projecting from one edge portion of said cover and having its outer terminal in electric connection with said cover, a conductor connected with said cover and adapted to be connected with one terminal of the battery, and a switch carried by said cover and adapted to complete the circuit from the 50 other lamp terminal to the other battery terminal.

2. An electric lantern comprising a dry 55 battery, a casing containing said battery having a removable cover comprising conducting material, an electric lamp carried by the flange of said cover and having its outer terminal in electric connection therewith, a reflector for the lamp also carried by the flange of said cover, a conductor connected with said cover and adapted to be connected with one terminal of the battery, and a switch carried by said cover and adapted to complete the circuit from the 65 other lamp terminal to the other battery terminal.

3. A device of the character set forth, comprising a casing having a top adapted to be opened and which is provided with a downturned flange, a dry battery in said casing having poles on its upper end, a laterally projecting lamp carried by said flange and having one terminal electrically connected with one battery pole and a switch carried by said top and adapted to complete the circuit to the other battery pole. 70

4. A device of the character set forth comprising a casing having a top provided with a downturned flange, a dry battery in said casing having poles at its upper end, a laterally projecting reflector having at its back portion an open-ended socket connected with the said flange, a lamp mounted in said socket, a contact member carried by said top and engaging the central terminal 80 of the lamp, electric connections between the outer lamp terminal and the other battery pole, and a switch device for completing the circuit. 85

5. A device of the character set forth comprising a casing having a top adapted to be opened and which is provided with a downturned flange and which serves as an electric conductor, a dry battery in said casing having poles at its upper end, a laterally projecting electric lamp carried by said flange and having one terminal electrically connected with said top, a contact member carried by said top and adapted to engage the other lamp terminal, electric connections between said top and one battery pole, and a switch electrically connected with the other battery pole, and adapted to complete the circuit to said contact member. 95

6. A device of the character set forth comprising a casing having a top adapted to be opened and which is provided with a downturned flange and which serves as an electric conductor, a laterally projecting reflector, and a lamp socket at the back portion thereof extending through said flange, an electric lamp extending through said socket, a contact member carried by the top and engaging the central terminal of said lamp, a battery in said casing, an electric conductor connecting said top to one pole of the battery and a switch carried by said top, adapted to complete the circuit to the other pole of the battery. 105 110 115

7. A device of the class described, comprising a dry battery having both of its poles at one end, a lamp support of conducting material adjacent the pole end of said battery, an electric lamp carried by said support and in circuit therewith as to one of its terminals, a contact member insulated from said support and with which the other lamp terminal is electrically connected when inserted to position, a switch member on said support for controlling the 120 125 130

circuit, and flexible electrical connections fixedly and detachably connected with the poles of the battery and electrically connected to said support and said switch member, respectively.

5 8. A device of the character described, comprising a dry battery, an electric lamp, a support provided with a downwardly projecting annular flange, said lamp being 10 movably fixed to said flange with its base lying within the confines thereof, and electrical connections to said lamp fixed to said support within said annular flange and whose free ends are adapted for fixed engagement with the poles of said battery.

15 9. A device of the character described, comprising a casing, a battery removably disposed therein, a cap for said casing provided with a downwardly projecting annular flange, an electric lamp removably fixed to said flange with its base lying within the 20 confines thereof, and electrical connections fixed to said cap within said annular flange

and whose free ends are adapted for engagement with the poles of said battery and 25 said lamp.

10 10. A device of the character described, comprising a dry battery having terminals at its upper end, a casing in which said battery is removably contained, a cover for said 30 casing having a depending flange, a reflector mounted on said flange, an electric lamp in the base-portion of said reflector, conductors carried by said cover and having detachable engagement with said terminals 35 of said battery, and means for making and breaking circuit between said conductors and said lamp.

In testimony whereof, I affix my signature in the presence of two witnesses this 18th day of March, 1914.
